UNITED STATES PATENT OFFICE

ROYALL H. BOYSTER, OF OXFORD, NORTH CAROLINA

AIRPLANE

Application filed November 23, 1928. Serial No. 321,418.

This invention relates to improvements in airplanes, an object being to provide means capable of being included in the structure of an airplane, which will increase its lifting power and control, and will permit the airplane to be operated with greater efficiency at low, as well as high flying speeds.

As is well known, the airplane obtains its greatest lift from the vacuum created upon the top of the wing, and it is the purpose of the present invention to increase the height or depth of this vacuum space by providing vertical walls of upwardly traveling air which extend above the wing and which act to draw the air between these walls upward, and as the walls of air meet at a point above the wing, the upper surface of the latter is divided into a number of relatively high vacuum chambers or spaces. Another object of the invention is the provision of means of the above character which may also be utilized to provide opposed resistance walls to materially assist in stabilizing the airplane, while these resistance walls applied to the ailerons and rudders, will give control of the airplane at low, as well as high flying speeds.

With the above and other objects in view, the invention further includes the following novel features and details of construction, to be hereinafter more fully described, illustrated in the accompanying drawings and pointed out in the appended claim.

In the drawings:

Figure 1 is a plan view of an airplane constructed in accordance with the invention.

Figure 2 is a side elevation of the rear end of the fuselage showing the rudders.

Figures 3 and 4 are enlarged sectional views taken respectively on the lines 3—3 and 4—4 of Figure 1.

Figure 5 is a plan view showing a slightly modified form of the invention.

Figure 6 is a view similar to Figure 2 but illustrating the form of the invention shown in Figure 5.

Referring to the drawings in detail where-in like characters of reference denote corresponding parts, the reference character 10 indicates the fuselage of an airplane from

which extends a wing or wings 11. The horizontal and vertical rudders of the airplane are indicated at 12 and 13 while the ailerons are shown at 14.

All of the foregoing elements may be of any preferred material and of suitable shape and size, the invention residing in providing combined lifting and resistance means for the elements mentioned which will increase the lifting power of the airplane and facilitate control at low flying speeds.

With the above purposes in mind, the invention provides spaced elongated slits 15 in the wing of the plane and in Figure 1 of the drawings these slits are disposed in the line of flight. The slits 15 extend through the wing and are formed by opposed side walls 16 and define vertically disposed passages, which, when the airplane is in flight will direct currents or walls of air upward above the upper surface of the wing. This upward movement of these air currents will create a suction and the air currents meeting at a point above the upper surface of the wing form separate or individual vacuum chambers or vacuum spaces of an appreciable depth so that the vacuum ordinarily existing over the upper surface of an airplane wing in flight will be materially increased due to the depth or height of these vacuum chambers or spaces. By this means, the lift of the wing will be materially increased and the airplane may be supported and controlled at lower flying speeds than is ordinarily possible. In addition, the walls 16 of these passages offer resistance to tilting so that the stability of the plane is increased.

By providing these passages and walls in the rudders 12 and 13, as indicated at 17, increased air resistance is offered by the rudders when the latter are manipulated, so that the direction of flight of the plane may be more readily controlled at low flying speeds.

In addition, the provision of the increased lifting power provided under the upper surface of the wing permits of a reduction in wing camber so that the wings offer less resistance to flight.

In Figure 5 of the drawings, the wing 18 and ailerons 19 have the slots disposed longi-

tudinally as shown at 20 so that longitudinally disposed air walls and lifting chambers are provided for the wings and ailerons.

The horizontal and vertical rudders 21 and 5 22 are provided respectively with laterally and upwardly extending slots 23 and 24 to offer resistance for the control of the plane.

The invention is susceptible of various changes in its form, proportions and minor 10 details of construction and the right is herein reserved to make such changes as properly fall within the scope of the appended claim.

Having described the invention what is claimed is:—

15 In an airplane, a wing including upper and lower walls having relatively narrow spaced slots and the slots of one wall alining with the slots of the other wall, and spaced pairs 20 of strips connecting the upper and lower walls and forming air passages in alinement with the alining slots of the walls, said slots disposed in the direction of flight of the device to divide the upper surface of the wing into separate vacuum chambers during the 25 flight of the airplane.

In testimony whereof I affix my signature.
ROYALL H. ROYSTER.
